Inventor
Augustinas Maculskiys
By his Attorney
George C. Heinrichs

UNITED STATES PATENT OFFICE.

AUGUSTINAS MACULSKIYS, OF NEWARK, NEW JERSEY, ASSIGNOR OF ONE-HALF TO
ADOMAS REMEIKIS, OF NEWARK, NEW JERSEY.

RING WATCH.

1,404,536.

Specification of Letters Patent. Patented Jan. 24, 1922.

Application filed February 26, 1921. Serial No. 447,930.

To all whom it may concern:

Be it known that I, AUGUSTINAS MACULSKIYS, a citizen of Lithuania, residing at Newark, county of Essex, and State of New Jersey, have invented certain new and useful Improvements in Ring Watches, of which the following is a specification.

The object of this invention is to provide a ring in which a watch may be inclosed in such a manner, that the proper time can always be told at a glance.

The bracelet or wrist watches which are generally in use at the present time, have the disadvantage that in order to consult the same, it is necessary to raise the arm in order to partly lift the sleeve and that they too easily turn around the arm so that the watch dial is frequently upon the wrong side of the arm, making an inspection inconvenient.

These disadvantages are successfully overcome by the object of the present invention, the principal feature of which is the provision of a ring presenting a seat for the watch in its rim or crown on which the watch is either seated from the top or from the bottom, but so that its dial at all times will be upwardly turned for ready inspection or consultation.

It is a further object of the invention to provide a ring watch seated in a socket of the ring, the winding and setting stem of which is normally embedded within a recess in the rim, flush with the outer face thereof.

A still further object of the invention is the provision of a watch of this character, the winding and setting stem of which may easily be positioned radially to the rim so that the watch may be readily wound up or set in the customary well known manner.

The invention consists in the novel construction, arrangement of parts and combination of elements and details, which will be more fully described hereinafter, and finally pointed out in the claims.

The preferred form of my invention is illustrated by way of example in the accompanying drawing, in which:

Figure 1 shows in side view a ring constructed according to the present invention adapted to carry a watch.

Figure 2 is a front elevation thereof.

Figure 3 is a top plan view.

Figure 4 shows in bottom plan view a modified form of ring mounting for a watch.

Figure 5 is a side view of the ring, Fig. 55 showing the watch separated therefrom.

As shown in Figures 1, 2 and 3 a watch 10 of any ordinary, well known construction is set from below into the rim 11 or crown 60 of a ring having the customary band 12, for instance in ornamental execution as illustrated at 13, and integrally made with the rim or crown thereof, having an upper opening through which the watch dial 14 is 65 visible, the outer flange 15 of the crown forming the frame for the dial.

A removable plate 16 covers the work of the watch and is adapted to rest with its outer face upon a finger bearing the ring. 70

The rim 11 is provided with a lateral recess for the reception of the outer end of the winding or setting stem 17 for the watch, which is connected to the winding and setting stem proper of the watch, which is extended into this recess, by a pin and slot connection 18 and 19 so that the stem may be shifted in a radial direction in the customary manner when it is desired to either set or wind the watch, while normally the 80 end 17 is so embedded in the recess of the rim that its end may be engaged by a finger nail to bring the end into its working radial position.

In Figures 4 and 5, a ring 20 is illustrated 85 having a rim or crown 21 constituting a socket 21' for the reception of the watch 22, adapted to be placed into the socket from above and to be secured therein in any well known manner.

The rim 21 as well as the watch rim 23 have recesses 24 and 25 respectively, which are in alignment with each other when the watch is placed into the socket and through which the end 17 of a setting stem is radially projecting as described above with respect to the preferred form illustrated in Figures 1, 2 and 3.

Having thus described my invention, what I claim as new and desire to secure by Letters Patent of the United States is:

A ring adapted to carry a watch, comprising a crown adapted to receive the watch and having an upper opening with the face

- or dial of said watch visible through said upper opening, a bottom flange on said crown adapted to support the back of the watch, an outer side flange on said crown provided with a lateral opening or slot allowing the passage of a pivoted radial stem for winding and setting the watch and permitting a reception of said stem flush with the outer face of said flange when not in use for presenting an unbroken ring surface and allowing an operation of said stem. 10
- 5 In testimony whereof I have affixed my signature.

AUGUSTINAS MACULSKIYS.
